UNITED STATES PATENT OFFICE.

JAMES R. KEISER, OF BROOKLYN, NEW YORK.

DESIGN FOR A NECKTIE.

SPECIFICATION forming part of Design No. 15,913, dated March 3, 1885.

Application filed December 12, 1884. Term of patent 3½ years.

To all whom it may concern:

Be it known that I, JAMES R. KEISER, of Brooklyn, in the county of Kings and State of New York, have invented and produced a new and original Design for Neckties, of which the following is a specification.

In the accompanying drawings, Figure 1 is a front view of a necktie embodying my design. Fig. 2 is a side or edge view thereof.

10 Similar letters of reference designate corresponding parts in both figures.

A A' designate two wing-like portions or aprons, shown as extending obliquely, and one, A', crossing the other, A. Above these 15 wing-like portions or aprons A A' is an upwardly-extending portion, B.

C designates the band of the necktie.

As shown, the upwardly-extending portion B extends above the aprons A A', and curves

upwardly and rearwardly, or, in other words, 20 is approximately in the form of a cylinder. It has a smooth surface. The band C extends outwardly from the ends of the portion B.

In the wing-like portions or aprons A A' are two curved plaits, a a', shown as curving 25 downwardly and then inwardly toward each other below the portion B.

What I claim as my design, and desire to secure by Letters Patent, is—

The design for a necktie, consisting of the 30 wing-like portions or aprons A A', having the curved folds or plaits a a', and the cylindrical portion B, extending upwardly above the aprons, substantially as described and shown.

JAMES R. KEISER.
